UNITED STATES PATENT OFFICE

HUGH R. MACMICHAEL, OF EL PASO, TEXAS, ASSIGNOR TO AMERICAN SMELTING AND REFINING COMPANY, OF NEW YORK, N. Y., A CORPORATION OF NEW JERSEY

SCOTCH-HEARTH FEEDING MECHANISM

Application filed June 22, 1927. Serial No. 200,524.

The invention relates to apparatus for metal smelting, and, more particularly, to a mechanical feeding mechanism for feeding and distributing the charge to a Scotch hearth 5 type furnace such as used in lead smelting.

According to the invention, a carriage is provided which moves back and forth along a Scotch hearth and which may have continuous motion during its operating trip. The 10 carriage is provided with mechanical feeding mechanism and may also be provided with mechanical poking or rabbling mechanism and mechanical shoveling or spreading mechanism. If desired, however, the rabbling and 15 shoveling may be done by hand.

The feeding mechanism, according to the invention, may comprise a suitable charge container preferably feeding into a suitable conveyor which delivers the charge to the 20 hearth. Suitable shaking mechanism may be provided to cause the charge to be fed and distributed in the desired manner. Suitable devices may be provided for controlling the distribution of charge to different parts of 25 the hearth. The relative distribution of charge across the width of the hearth and throughout the length of the hearth may be conveniently regulated and changed as occasion demands.

30 Various other features and advantages of the invention will be apparent from the following particular description and from an inspection of the accompanying drawings.

The invention also consists in certain new 35 and original features of construction and combinations of parts hereinafter set forth and claimed.

In the accompanying drawings, there is 40 shown for purposes of illustration one form of a device embodying the invention, in which

Fig. 1 is a side elevation of the carriage equipped with the feeding mechanism, looking toward the back of the furnace;

Fig. 2 is a top view taken on the line 2—2 45 of Fig. 1;

Fig. 3 shows an end view of the carriage and feeding mechanism and a section through the furnace;

Fig. 4 is a detail showing the construction 50 of the shaking mechanism, and

Fig. 5 is a detail showing the controlling gates for controlling the flow of the charge.

Like reference characters denote like parts in the several figures of the drawings.

In the following description and in the 55 claims parts will be identified by specific names for convenience, but they are intended to be as generic in their application to similar parts as the the art will permit.

Referring now to the drawing, and, more 60 particularly to Fig. 3, so much of a Scotch hearth as is necessary to an understanding of the invention will be described. The hearth comprises the usual trough 1, relatively shallow and narrow, but comparatively long. At 65 the front end of the trough is a forwardly and slightly downwardly sloping apron 2. At the back of the trough is the furnace back which has a hollow space 3, in which cooling water may be circulated, below which are 70 series of tuyères 4, extending the length of the furnace for supplying the necessary draft, as is well understood. Above the back is a canopy or hood 5 for catching the fumes and gases given off by the furnace. This 75 construction is well known and no further description is deemed necessary.

Extending along in front of the furnace are two overhead track rails 6 supporting a 80 traveling carriage 12. The traveling carriage is supported by two axles 7 and 8, each axle having two wheels 9 and the carriage is made up of suitable structural members. The carriage may support suitable rabbling and 85 shoveling mechanism (not shown) and also supports the feeding mechanism which is described more in detail hereinafter.

For driving the carriage 12 a separate electric motor 10 is provided. One of the axles 8 has a cog wheel 11 secured thereto, this cog 90 wheel being connected to another cog wheel 14 which is operatively connected to the motor 10 through a suitable worm drive reduction unit 15. It will be understood that the wheels 9 are rigidly secured to the axle 8. 95

The motor 10 is of the reversible type and may have provision for running at an increased speed when reversed. The carriage is adapted to move along in front of the hearth, and on its operating trip the motor 100

causes the carriage to travel at reduced speed. The carriage may be provided with a reversing switch (not shown) for controlling the motor 10. At the end of its operating 5 trip the reversing switch lever may hit a suitable stop (not shown) which causes the motor 10 to reverse, thereby causing the carriage to return to its starting position at increased speed. At the starting position the switch 10 lever may hit another stop (not shown) which causes the motor to reverse again, thereby causing the carriage to travel on its operating trip at the reduced speed.

For operating the feeding mechanism, a 15 separate motor 16 is shown, this motor having drive connection with a counter shaft 17 supported in suitable bearings in the frame. An intermediate shaft 18 is positioned between the motor and the counter shaft, the intermediate shaft having a large gear 19 meshing a smaller gear 20 on the motor shaft, and a smaller gear 21 meshing a larger gear 22 on the counter shaft.

The carriage frame supports a suitable 25 charge container or hopper 25 into which the charge, which may be pre-mixed ore, fume and fuel finely divided, may be delivered in any desired way. The hopper 25 tapers downwardly as shown in Figs. 1 and 3. The 30 bottom wall of the hopper is closed and the side has an opening forming a mouth 23. Beneath the hopper is an inclined chute or table 26, this chute extending backwardly toward the furnace and slightly downwardly, 35 as shown in Figs. 2 and 3. The chute is suitably sub-divided by longitudinal walls 27 forming a number of smaller troughs or conduits 28. The end of the chute 26 is cut at an angle of about 45° so that the charge which 40 is fed down the troughs 28 may be fed and distributed throughout the width of the hearth as shown in Fig. 2.

The chute 26 is suitably mounted on the frame by means of four mountings 29, these 45 mountings each consisting of a casing in which is disposed a suitable spring means so that a considerable play or shaking action may take place between the chute and the carriage frame, as hereinafter described more in 50 detail. Depending from the chute 26 is a pair of bearings 30 in which is journalled a shaker shaft 31 having unbalanced weights 32 fixed thereon.

For controlling the flow of charge down the 55 several troughs 28, individual gates 33 are provided at the mouth of the hopper 25, these gates each running on suitable guides and having a hand screw 34 for holding it in the proper position. These gates may be used 60 for regulating the relative amounts of charge fed down the several troughs.

A sprocket 37 may be loosely mounted upon the counter shaft 17, and a clutch 38 may be provided for connecting and disconnecting 65 the sprocket to the counter shaft.

An intermediate shaft 39 may be provided having a small sprocket 40 and a large sprocket 41 thereon, and a chain 42 may connect the smaller sprocket with the sprocket 37 on the counter shaft. A sprocket 43 may be provided on the shaker shaft and a chain 44 may connect this sprocket with the larger sprocket 41, on the intermediate shaft 39. It will be seen that this sprocket and chain arrangement operates to speed up the shaker shaft. It will be understood that the relatively low speed of the counter shaft 17 is necessary for driving the other operating mechanism, such as rabbling and shoveling mechanism, (not shown) which may be 80 mounted on the carriage.

The clutch 38 is controlled by a suitable control linkage operated by the movement of the carriage. Extending along the hearth and throughout substantially the extent of the carriage travel is a control rail 47, the ends 48 thereof sloping away from the carriage. A control lever 49 having a roller 50, engages the control rail 47 to operate the control linkage. The control lever 49 is pivoted to the frame at 51 and is connected through link 52 to clutch lever 53 pivoted to the frame at 54. The clutch 38 is provided with a grooved collar 55 in which rides a collar 56 having pivoted connection with clutch 95 lever 53.

When the carriage is traveling its operating trip as shown by the arrow in Fig. 2, the operating lever is in the position denoted by A in Fig. 2, and the clutch 38 is engaged, 100 thereby causing the feeding mechanism to be operated. When the carriage reaches the end of its operating trip, the control lever 49 will run off the end 48 of control rail 47. The clutch spring and, if desired, auxiliary 105 spring 59 will cause the control lever 49 to assume a neutral position, as indicated by B in Fig. 2, in which position the clutch 38 is disengaged and the feeding mechanism stops.

During the back trip of the carriage, the control lever 49 assumes an opposite position as indicated by C, but this has no effect upon the engagement of the clutch, the feeding mechanism remaining inoperative. When the control lever 49 runs over the starting end 48 of the control rail 47 it again assumes its neutral position, and, when the carriage begins its next operating trip, the control lever assumes a position to operate the clutch and cause the feeding mechanism to function.

The slope of the chute 26 is not sufficient to cause the charge to flow down unless the chute is shaken. When the clutch is engaged, it will be seen that the driving mechanism will cause the chute to shake or vibrate, the loose spring mountings 29 allowing this action. As the carriage travels on its operating trip, the charge will be fed down the 130

troughs 28, and its distribution on the hearth will be controlled by the opening of the gates

33. The arrangement is such that very accurate control of spreading may be obtained, and by pre-mixing the fuel, ore and fume, a very efficient smelting action may be obtained. The poking operation followed by the leveling or shoveling operation above described may precede the feeding operation, 10 and the poking and shoveling operations as above described, may be performed by apparatus (not shown) mounted on the carriage, or may be performed by hand.

Thus an automatic feeding mechanism has 15 been provided for a lead smelting Scotch hearth which is effective and efficient in operation. The distribution of charge on the hearth can be nicely controlled to meet different operating conditions imposed by various causes such as changes in the ore and in the condition of the fire. The relative distribution across the hearth may be controlled by operation of the gates to allow different amounts of charge to be fed down the several troughs. The relative distribution along 20 the length of the hearth may be controlled by changing the position of the gates along the path of travel of the carriage. The arrangement is simple and rugged in construction, insuring long life and small expense of 25 upkeep. The feeding mechanism requires no great skill to operate and yet aids materially in maintaining a uniform and effective fire throughout the hearth, resulting in maximum metal recovery from the ore.

While certain novel features of the invention have been shown and described and are pointed out in the annexed claims, it will be understood that various omissions, substitutions and changes in the forms and details of 40 the device illustrated and in its operation may be made by those skilled in the art without departing from the spirit of the invention.

What is claimed is:

45 1. In combination with a metallurgical hearth having a relatively long and narrow basin, a support, means for moving said support relatively to said hearth, a source of supply of charge on said support, a distributing chute receiving charge from said source and slightly sloping towards and over said basin perpendicularly thereto, said chute comprising a plurality of troughs, means for individually controlling the flow of charge 50 down each trough, the end of said chute extending diagonally with the length of said basin, and means for shaking said chute.

55 2. In combination, a lead smelting hearth comprising a relatively long and narrow basin, a support, means for moving said support relatively to said hearth at a uniform rate, means on said support for delivering a stream of charge to said basin, and means for controlling the distribution of said stream 60 across the width of said basin during the

relative movement of said hearth and support.

3. In combination with a metallurgical hearth having a longitudinally extending basin, mechanical feeding mechanism comprising a carriage adapted to travel along said hearth, a hopper on said carriage, an inclined chute below the mouth of said hopper extending over said basin, the end of said chute being disposed across said basin, said chute being divided up into separate feed troughs, said mouth having gates, one for each feed trough, spring mountings between said chute and carriage, a shaker shaft journaled on said chute and having unbalanced weights, devices mounted on said carriage for driving said shaker shaft, and means controllable by the movement of said carriage for controlling said devices.

4. In combination with a metallurgical hearth having a longitudinally extending basin, mechanical feeding mechanism comprising a carriage adapted to move along in front of said hearth, a motor on said carriage, a hopper on said carriage having a mouth at the bottom thereof, an inclined chute having one end below said mouth and the other end over said basin, said chute having its discharge end extending across said hearth, walls dividing said chute into a plurality of feed troughs, said mouth having controllable gates, one for each feed trough, spring mountings between said chute and carriage, a shaker shaft journaled on said chute and having unbalanced weights, and means for driving said shaker shaft by said motor.

5. In combination with a hearth having a longitudinally extending basin, mechanical feeding mechanism comprising a carriage adapted to move along in front of said hearth, means including a separate motor for imparting a continuous movement to said carriage on its operating trip, a second motor on said carriage, a counter shaft below said second motor, reduction gearing connecting said second motor and counter shaft, a hopper on said carriage having a mouth at the bottom thereof, an inclined chute having one end below said mouth and the other end over said basin, said chute having its discharge end cut at substantially 45 degrees with the length of said hearth, walls dividing said chute into a plurality of feed troughs, said mouth having a controllable gate, one for each feed trough, spring mountings between said chute and carriage, a shaker shaft journaled on said chute and having unbalanced weights, a shaker sprocket loosely mounted on said counter shaft, a clutch controlled by the movement of said carriage for connecting said sprocket to said counter shaft, an intermediate shaft, and sprockets and chains for driving said shaker shaft by said shaker sprocket through said intermediate shaft.

6. Smelting apparatus comprising a lead-smelting hearth having a relatively long and narrow charge-holding basin, a carriage, means for moving said carriage with a continuous movement along said hearth, a distributing device on said carriage extending over said basin, said distributing device comprising a plurality of chutes sloping slightly and extending to different points across the 10 width of said basin, the end of each chute being disposed at an angle to the length of said basin, means for shaking said distributing device to feed charge to said basin, a charge container on said carriage feeding said 15 distributing device, and means for individually controlling the flow of charge in each chute to control the distribution of charge across said basin.

7. Smelting apparatus comprising a lead-smelting hearth having a relatively long and narrow charge-holding basin, a carriage, means for moving said carriage with a continuous movement along said hearth, a distributing device on said carriage extending 20 over said basin, said distributing device comprising a plurality of chutes sloping slightly and extending to different points across the width of said basin, means for shaking said distributing device to feed charge to said basin, a charge container on said carriage feeding said 25 distributing device, and means for individually controlling the flow of charge in each chute to control the distribution of charge across said basin.

35 8. Smelting apparatus comprising a metal-smelting hearth having a relatively long and narrow charge-holding basin, a carriage, means for moving said carriage along said hearth, a distributing device on said carriage extending over said basin, said distributing device comprising a plurality of conduits extending to different points across the width of said basin, means for individually controlling the flow of charge through 40 each conduit to control the distribution of charge across said basin, and means for supplying charge to said distributing device.

45 In testimony whereof I have hereunto set my hand.

50 HUGH R. MACMICHAEL.
